UNITED STATES PATENT OFFICE

PATRICK J. CONLEY, OF CANTON, OHIO

WALL BEARING CERAMIC TILE

Application filed December 9, 1929. Serial No. 412,713.

The invention relates to tiles and more particularly to wall bearing ceramic tiles which may be in the form of a standard brick or building block.

In the installation of tile walls on the interiors of buildings, it is customary to first erect a wall of bricks, building blocks or the like, after which the interior surface of the wall is covered with tiles to produce the desired effect.

Such a construction is very costly and for this reason, although many architects prefer tile wainscoting in public buildings, it is ordinarily not economically practical to use the same in the average public building such as schools and the like.

The object of the present improvement is to provide a wall bearing ceramic tile in the form of an ordinary brick or building block having the surface on one or both sides glazed, enameled or salt-glazed and formed to represent a plurality of tiles by providing vertical dove-tailed grooves in the surface of the brick or block to produce false mortar joints.

With the improved tile, it will be seen that when the brick wall is laid up, the interior surface is a finished tile wall, eliminating the material cost and labor required to put the tile finish on the surface of the wall.

Another object of the improvement is to perforate the bricks or blocks vertically to decrease their weight and to provide for a lock bond for the mortar used in laying up the wall.

An embodiment of the invention is illustrated in the accompanying drawings, in which

Figure 1 is a perspective view of a portion of a wall built of the improved tile;

Fig. 2, an enlarged perspective view of one of the tiles;

Fig. 3, a similar view of a special tile for use at the end of a wall; and

Fig. 4, a perspective view of a special tile for use at the top of a wainscoting or the like.

Similar numerals refer to similar parts throughout the drawings.

The improved tile, as indicated generally at 10 in Fig. 2, may be of the general size and shape of an ordinary brick or building block

and is preferably provided with vertical openings 11 to decrease the weight of the article and at the same time permit the mortar to enter the same to form a lock bond when the tiles are laid up in a wall.

One or both side surfaces of the tile may be divided by a vertical dove-tailed groove 12 dividing the surface into two substantially square areas as shown at 13, which may be glazed, unglazed enameled or salt-glazed as desired to produce different tile effects thereon.

In laying up a wall with the improved wall bearing tile the same may be done in the manner of laying up the ordinary brick wall and by using the usual half-bond, a tile effect such as shown in Fig. 1 is produced, the square areas 13 upon the surfaces of the tiles being located in vertical and horizontal alinement. False mortar joints are produced by filling the dove-tailed grooves 12 with mortar, giving the effect, in the finished wall, of a tiled surface.

For finishing the ends of walls, such as indicated generally at 14 in Fig. 1, special tiles such as in Fig. 3 may be provided. Each of these tiles is substantially the same as illustrated in Fig. 2, excepting that at one end the vertical corner is rounded as at 15 and the surface of the tile is divided by the dove-tailed vertical groove 12 into the areas 13 and 13a, the latter having the rounded corner 15 to finish the end of the wall.

Where wainscoting and the like is constructed of the improved tiles, the upper course 16 may be formed of special tiles such as shown in Fig. 4, each having one side surface shaped as at 17 to produce a ridge or ledge along the top of the wainscoting. The dove-tailed groove 12 is also provided through the center of the finished surface of this tile in order to carry out the false mortar joint.

Where it is desired to have a glazed double wall, as indicated generally at 18, in Fig. 1, the tile effect may be provided on both sides of the wall, tiles such as shown in Fig. 2 with vertical grooves 12 upon opposite sides being used for this purpose.

The improved tiles may be cut or broken at

any point in the same manner as the ordinary brick in order to finish out at the ends of the wall and permit the same to be laid up in the wall using a half-bond, quarter-bond or 5 in any other manner desired.

This structure eliminates the mortar joints at the ends of a wall, as best shown in Fig. 1. It should be understood that many other special shapes, besides those illustrated, may 10 be made without departing from the invention, carrying out the scheme shown in the drawings, by providing the vertical dovetailed grooves upon the finished surface of the tiles.

15 For instance, as shown in Fig. 1, where it is desired to provide a glazed double wall as shown at 18, the upper course 19 may be of the shape shown, having the ridge or ledge 17a formed on each side.

20 By glazing or otherwise tile finishing the ends of the tiles, as shown at 20, in Fig. 1, a partition wall, such as shown at 18 in said figure, having an exposed end, may be built.

The improved tile may be made in the size 25 and shape of a standard brick or building block or the size and shape may be varied to produce different effects without departing from the invention.

From the above it will be obvious that there 30 are many advantages in the improved wall bearing tile, one principal advantage being that it eliminates the necessity of first laying up a brick wall and then putting a tile finish on the same as with this structure, when the 35 wall is laid up, the surface thereof is a finished tile wall which is produced for practically the same cost as the ordinary brick wall.

I claim:

40 A wall bearing brick provided on a side surface with a vertical dovetail groove forming a false mortar joint and dividing said surface into two substantially square areas each of which is surface finished to represent 45 a tile, where by a wall built of said bricks will have a finished inner surface having the appearance of tiles provided with continuous vertical and horizontal mortar joints.

In testimony that I claim the above, I have 50 hereunto subscribed my name.

PATRICK J. CONLEY.
